Primary Examiner—Cathy Anne MacCormac

(57) **CLAIM**

The ornamental design for a printer, as shown and described.

DESCRIPTION

FIG. 1 is a right-front-top perspective view of a printer showing the new design;

FIG. 2 is a left-rear-bottom perspective view thereof;

FIG. 3 is a front elevation view thereof;

FIG. 4 is a rear elevation view thereof; and,

FIG. 5 is a left side elevation view thereof.

The broken lines showing the paper tray are for illustrative purposes only and form no part of the claimed design.
